INK RIBBON FEEDING AND INK RIBBON POSITIONING MECHANISM FOR PRINTING MACHINES

Horace S. Beattie, Poughkeepsie, N. Y., assignor to International Business Machines Corporation, New York, N. Y., a corporation of New York

Application June 10, 1950, Serial No. 167,378

10 Claims. (Cl. 101—336)

1

This invention concerns ink ribbon mechanisms for use in printing devices incorporated in various forms of machines embodying such printing devices as typewriters, accounting machines, check printing machines, etc. where it is customary to use an ink ribbon.

The object of the invention is to provide an ink ribbon feeding mechanism of such design and arrangement that it will increase the acceptable life of an ink ribbon by enabling inking through as much of the ribbon as practical, instead of the usual single horizontal line along its length. By securing the inking through most of the ribbon the effective life of a ribbon is increased because the available inking area can be very thoroughly, effectively and evenly utilized. Also failure due to mechanical damage is practically eliminated since the wear is more evenly distributed over the entire ribbon.

In the present machine this object is attained by feeding the ink ribbon not only lengthwise but transversely up and down so that inking is effected through at least two different areas but preferably through four different areas lengthwise of the ribbon to more evenly distribute the wear over the entire ribbon. One means of accomplishing the object of the invention is shown in the preferred embodiment herein by utilizing two of these longitudinal areas in one direction of the feed of the ribbon and then utilizing the other two inking areas in the other direction of the feed of the ribbon, and shifting the ribbon up or down for selection of the two areas during or after the feeding of the inking ribbon.

A still further object is to incorporate an automatic ribbon reverse mechanism to provide not only the change in direction of the feeding of the ink ribbon but to also position the ribbon so that two other areas are selected and used successively as the ribbon is moved up and down during the reverse direction of feed of the ribbon.

Another object is to provide an improved ink ribbon reversing control device which is preferably electrical in construction and with associated devices for selecting a different longitudinal area for inking when the direction of feed is reversed.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view showing the operative association of the improved ink ribbon and ink ribbon feeding mechanism with a printing device of any suitable printing or typing machine.

2

Fig. 2 is a detail view showing how the contact operating mechanism is controlled by the unwinding of the ink ribbon on a spool to close contacts which reverse the direction of feed of the ribbon.

Fig. 3 is a detail view of a pawl and ratchet ink ribbon spool driving device which is associated with the left-hand ribbon spool for winding up the ink ribbon on this spool.

Fig. 4 is a view in side elevation showing the left-hand ribbon spool in an elevated position, which position is taken when the ink ribbon is being unwound from this spool.

Fig. 5 is a transverse sectional view taken on the line 5—5 of Fig. 1 and shows, apart from the constructional details of the left-hand ink ribbon spool and driving device the position that the left-hand ribbon spool takes when the inking ribbon is being wound on this spool.

Fig. 6 is a view showing the construction of the right-hand ink ribbon spool and the position that this ribbon spool takes when the ink ribbon is being unwound from this spool and onto the left-hand spool.

Fig. 7 is a sectional view taken on the line 7—7 of Fig. 6.

Fig. 8 is a detail view of the pawl and ratchet ribbon spool driving device associated with the right-hand ribbon spool for winding the ink ribbon on this spool.

Figs. 9 to 13 inclusive are diagrammatic views which show the different positions that the ink ribbon assumes in various operations of the machine.

35 Of these views:

Fig. 9 shows the diagonal position that the ink ribbon assumes in a rest position of the machine.

Fig. 10 shows the position the parts assume during an operation of the machine in which the ink ribbon is being unwound from the left-hand spool and onto the right-hand spool and printing is effected through the D inking area.

Fig. 11 shows the position of the parts in the following machine operation, the ink ribbon being fed in the same direction but inking now being effected in this machine operation through the C area of the inking ribbon.

Fig. 12 shows the position of the parts when the ribbon reverse mechanism has been rendered effective for changing the position of the ink ribbon and winding the inking ribbon on the left-hand spool and unwinding it from the right-hand spool, printing now being effected in this cycle of machine operation through the A inking area.

Fig. 13 shows the position of the parts taken in the following machine operation for effecting inking through the B area, the ribbon still being fed in the same direction as in Fig. 12.

Fig. 14 is a sectional view on an enlarged scale and taken on the line 14—14 of Fig. 5.

Fig. 15 is an electrical wiring diagram of the electrical instrumentalities.

The power for driving both the left-hand and right-hand ink ribbon spools is derived from the main drive shaft 10 (Fig. 5) and said shaft carries a gear 11 meshing with a gear 12 secured to a short shaft 13 which carries a worm 14. Said shaft 10 is driven one revolution for each machine cycle, i. e. for each printing operation.

Shaft 10 preferably corresponds to shaft 39 of the patent to R. E. Page et al., No. 2,438,071 wherein it will be seen that this shaft is driven with a uniform speed at times and a slower speed during printing time which is about one-fourth of its uniform speed. Thus, while in the present machine the ink ribbon is being fed about one inch for each machine cycle and shifted transversely at the same time the reduced speed of the drive shaft 10 during printing time causes very little ink ribbon feed longitudinally, which is about .03 inch in the preferred embodiment. In fact, the extent of feed is so small that the ribbon can be regarded as practically stationary during printing operations.

The worm 14 meshes with a worm wheel 15 secured to the lower end of a vertical drive shaft 16 which is the drive shaft for the left-hand spool. The vertical drive shaft 16 rotates in ball bearings 17 and 18, both of which are carried by a casting 19 to thus support the drive shaft 16 vertically and also to provide a support and mounting for other parts comprising the left-hand ink spool and the drive therefor.

Mounted at the upper part of the vertical drive shaft 16 above the upper face of casting 19 is a sleeve 25 provided with three similar longitudinally formed key-way slots 26 (Figs. 5 and 14). At the upper end of the vertical drive shaft 16 there are provided three key-way slots 27 which, in conjunction with the three aligned slots 26 in the sleeve 25 receive balls 28 which, in effect, comprise keys between the sleeve 25 and the vertical drive shaft 16. Just below this connection a similar key connection is arranged so that the drive shaft 16 and sleeve 25 are securely keyed together. Thus, the sleeve 25 will rotate with the drive shaft but an independent movement of the sleeve 25 upwardly and downwardly may be effected through the provision of the short key-way slots 27. A spring 30 fitting in an annular recess in the lower part of sleeve 25 and encircling the drive shaft 16 bears against the sleeve 25 and a washer 21, the compression of the spring normally urging the sleeve 25 upwardly to the position shown in Fig. 4. Upward movement of washer 21 is restrained by a shoulder 22 of shaft 16 and spring 30 causes washer 21 to bear against the inner race of ball bearing 18, so that sleeve 25 thus rotates on ball bearing 18. The keys just described also hold sleeve 25 in its most upward position when released and moved to this position by spring 30.

The ribbon spool carrier 32 has attached thereto a hub 33 which loosely encircles the upper portion of the sleeve 25 and the bottom face or flange of the spool carrier 32 has attached thereto a ring 34 bearing against the flange of the sleeve 25 and which consists of a suitable material which provides a frictional connection between the spool carrier 32 and the flange of sleeve 25. Mounted within longitudinal circular recesses of the spool carrier 32 are spring-urged balls 35 which bear against a plate 36 held to the

upper extremity of the sleeve 25 by a split spring washer 37 fitting in an annular groove formed in the sleeve 25. Thus, the spring-pressed balls 35 bearing against the fixed plate 36 urges the spool carrier downwardly so as to frictionally contact the flange of sleeve 25. This frictional connection between the sleeve 25 and the spool carrier 32 assists a pawl driven mechanism now to be described to cause the spool carrier support to rotate therewith as the ribbon is being wound onto the ribbon spool 38. When the ribbon is being unwound from the ribbon spool 38, the ribbon spool support 32 rotates in a direction opposite to the sleeve 25 and the frictional connection provides the proper tautness for the ribbon at the printing line.

The ribbon spool 38 fits over the upper portion of the spool carrier support 32, and, to cause the ribbon spool 38 to rotate therewith, the ribbon spool 38 has an inwardly extending tab 40 (Fig. 14) which fits in a longitudinal slot 41 of the spool carrier 32. Thus, the ribbon spool 38 positively rotates with the spool carrier support 32 when the ribbon is being wound onto the spool or unwound from this spool to be wound on the other ribbon spool, in a manner which will be subsequently explained.

The gearing between the main drive shaft 10 (Fig. 5) and the vertical drive shaft 16 is designed to effect a 60° rotation of the latter or $\frac{1}{6}$ of a revolution, and through a pawl and ratchet mechanism now to be described rotate the left-hand ribbon spool 60° when the ink ribbon is to be wound thereon for every machine cycle, which corresponds to each revolution of the main drive shaft 10. Pinned to the extremity of the drive shaft 16 is a ratchet disk 45 having, as best shown in Fig. 3, upwardly formed ratchet shaped teeth. Attached to the ribbon carrier 32 by a pair of screws 46 is a bracket 47. Pivotally mounted on a stud 48 carried by said bracket is an operating pawl 49 which is urged by a spring 50 to engage a tooth of the ratchet disk 45 when pawl 49 is in certain positions. When the ribbon spool occupies the lowest position shown in Fig. 5 and the one step higher position, effected by means to be subsequently described, the operating end of the pawl 49 will, by means of spring 50, engage in both positions, (full line and dotted in Fig. 3) the ratchet disk 45. The engaging end of the pawl 49 and the ratchet teeth of the disk 45 are so designed and proportioned that the operating end of the pawl 49 will be in direct engagement with the straight edge of one of the teeth so that the 60° movement of the drive shaft 16 will, through the ratchet disk 45 and pawl 49, rotate the spool carrier support 32 and thus the ribbon spool 38.

However, in the extreme upward movement of the ribbon spool and the pawl 49, the latter will be rocked by its spring 50 to engage a stop stud 51 carried by the bracket, and in this extreme highest position of the ribbon spool and pawl 49 and also one step below, as in Fig. 4, which is effected by means to be presently described, pawl 49 will be held out of engagement with the ratchet disk 45. This upward position of the ribbon spool and its next lower position are the positions that the ribbon spool occupies whenever the ribbon is unwound from the left-hand spool and wound on the right-hand spool which latter is shown in Figs. 1, 6 and 7.

It will be understood, therefore, that the ribbon and ribbon spool 38 have four different positions; A, B, C and D (Fig. 10). The two lower

positions C and D are selected when the ribbon is being fed from left to right, at which time a magnet 60 is deenergized (see Figs. 10 and 11) and each of these two lower C and D positions is selected by the rotated position of a cam 61 which is an integral part and forms a lower flange of the sleeve 25. However, when the solenoid 60 is energized to feed the ribbon from right to left and to select by the position of cam 61 either of the two uppermost positions A and B of the ribbon, the operating pawl 49 engages the ratchet disk 45. Therefore it will be understood that solenoid 60 is energized whenever the feeding of the ribbon is to take place from the right-hand spool to the left-hand spool, as shown by arrows diagrammatically in Figs. 12 and 13, and is deenergized whenever the ribbon is to feed from left to right, as in Figs. 10 and 11.

Secured to the casting 19 (Fig. 5) is a bracket 62 on which is pivoted at 63 a follower arm 64 which fits in a side recess 65 formed in the extremity of the core 66 of the solenoid 60. A compression spring 67 bears against a ring 68 on the core to force it against a pin 70 carried by the core 66 and a plate 69 attached to the casting 19. Spring 67 normally urges the core 66 to its upward position when solenoid 60 is deenergized. However, the coil spring 30 is a superior spring and urges the sleeve 25 upwardly so that cam 61 will continuously make contact with the roller at the extremity of the follower arm 64. For each 120° the cam 61 is provided with a high part 61H and a following low part 61L, each of which is a 60° segment on the diameter of the cam. Hence, for one $\frac{1}{6}$ th of a revolution of the sleeve 25 the roller of the follower arm 64 will drop from the high part 61H, as shown in Fig. 4, to the low part 61L. During the next cycle, if the arm 64 be held down due to the continued energization of the solenoid 60, the roller will then be raised from the low part 61L to a high part 61H of the cam. Thus, the ribbon spools will be taking a different vertical position during the feeding of the ink ribbon for each $\frac{1}{6}$ revolution of the sleeve 25, and at the time of printing a new area will be in position for inking.

From Fig. 10 it will be seen diagrammatically that the ribbon from which inking is to be effected comprises four longitudinal areas, the lines adjacent letters A, B, C, and D designating the center lines of the four areas A, B, C, and D from the top to the bottom.

When the solenoid 60 is deenergized the ribbon spool 38 will be held by spring 30 in its lowermost position with respect to the printing line so that areas C and D will be the inking areas at the printing line, and selected in alternation depending upon the position of the cam 61, as shown in Figs. 10 and 11. Hence, during one machine cycle when the low part 61L cam 61 is effective, inking will be derived from the D area of the ribbon, as shown in Fig. 10. In the next machine cycle cam 61 having rotated $\frac{1}{6}$ of a revolution to render the high part 61H effective, inking will be provided by the C area (as shown in Fig. 11) but since the ribbon has been fed from the left-hand spool to the right-hand spool (solenoid 60 being deenergized), a new portion of the ribbon will be always used for inking.

When the ribbon is to be fed from the right-hand spool to the left-hand spool, solenoid 60 is energized, at which time the follower arm 64 takes the position shown in Figs. 5, 12 and 13 and moves the spool 38 downwardly against the action of spring 30. As shown in Figs. 5 and 12

the high part 61H cooperates with the follower arm so that printing can be effected through the A area of the inking ribbon. During the next machine cycle, cam 61 having been rotated $\frac{1}{6}$ of a revolution (see Fig. 13) and the ribbon fed, the ribbon spool will be in such position that inking will be provided in this machine cycle by the B area as shown in Fig. 13 but a fresh portion of the ink ribbon will be presented to the printing devices.

Associated with the left-hand ribbon spool and its drive are electrical contacts controlled by the ribbon on spool 38. These contacts are closed to reverse the direction of feed of the inking ribbon so that it will next be drawn or unwound from the left-hand spool and fed or wound onto the right-hand spool, as well as to operate certain other interlock contacts, the purpose of which will be later explained in connection with the wiring diagram.

Secured to the bottom of the ribbon spool carrier 32 is a detent plate 75 which, as shown in Fig. 1, is scalloped to provide extended circular portions 76 which are in the path of a detent pawl 77 (see Figs. 1 and 4). Secured to the casting 19 is a bracket 78 which is slotted so that by means of a pivot 79 passing through the slot the detent pawl 77 may be pivoted. A spring 80 normally urges the extremity of the detent pawl 77 in the detent position shown in Fig. 4 and also in a detent position in the next lowermost position of the ribbon spool which, it will be recalled, are the two positions that the ribbon spool occupies when the ribbon is to be unwound from the left-hand spool. When the solenoid 60 is energized to lower the ribbon spool and to cause the drive of the left-hand spool to wind the ribbon thereon the pawl 77 will be held up in the position of Fig. 4, being stopped by a bracket portion 81 allowing the detent plate 75 to be moved out of engagement with detent pawl 77 and allowing a free rotation of the left-hand ribbon spool when the ribbon is being wound on the spool.

The right-hand ribbon spool shown in Figs. 6, 7 and 8 and the drive therefor are substantially the same as the left-hand drive and the description need not, therefore, be repeated. However, the major differences in construction and operation will be pointed out so that it will be more clearly understood how the ribbon is unwound from the left-hand spool and wound on the right-hand spool when a related solenoid 85 (Fig. 1) is energized.

It will be seen that the shaft 10 extends to the right and carries at its extremity a worm 86 (Fig. 6) meshing with a worm wheel 87, which latter is carried by the vertical drive shaft 88 for the right-hand ribbon spool 90. It will be seen, therefore, that the drive shaft 10 will also rotate the vertical drive shaft 88 but in an opposite direction. The vertical drive shaft 88 is rotated clockwise, as viewed in Fig. 1, $\frac{1}{6}$ of a revolution for each machine cycle, whereas the vertical drive shaft 16 rotates counterclockwise $\frac{1}{6}$ of a revolution in the same machine cycle.

It should be noted further that while the two lowermost positions of the left-hand ribbon spool 38 are the positions necessary for feeding the ribbon to spool 38, the right-hand spool 90 is in a position for feeding the ribbon to spool 90 when it is at its two highest positions. This reversal in positioning enables the diagonal position of the ribbon as shown in Fig. 9. When the machine is idle, that is to say, the drive shaft 10 is not turning, neither of the two solenoids 60 or 85 is en-

ergized, placing the inking ribbon in the diagonal position shown in Fig. 9. This facilitates insertion of forms in the platen carriage without interfering with the inking ribbon.

The core 91 of the solenoid 85 is provided with a slot 92 (Figs. 6 and 7) in which fits the vertical arm of a follower bell crank 93, the horizontal arm thereof having a roller cooperating with a cam 94. This cam is exactly, with respect to its cam formations, as the cam 61 but is so timed that when the cam 61 has its low portion effective a high portion of cam 94 will also be effective (see Fig. 9, for example). Thus, there will be a simultaneous up or down movement, or shift of the ribbon at each end in successive machine cycles. The cam 94 extends downwardly just the reverse as the cam 61, and, to cause it to have a continuous cooperation with the bell crank follower arm 93, the spring 95 (Fig. 6) is placed between the ratchet disk 96 and a washer plate 97.

Fig. 8 shows the relationship of the feeding pawl 98 and the ratchet disk 96. The feeding operation is substantially as has been described for the left-hand spool, the only difference being in the shape of the feeding pawl and the fact that the ratchet plate 98 has its teeth extending downwardly so that only in the upper two positions of the ribbon spool will the ribbon be wound upon the right-hand spool. In these two upper positions the printing will be effected through the C and D longitudinal areas of the inking ribbon (see Figs. 10 and 11).

The right-hand ribbon spool 90 also has a detent plate 98A (Fig. 1) with which a detent pawl 99 cooperates, similar in function and operation to detent plate 75 and detent pawl 77. It will be obvious that in an idle position of the machine, when neither solenoid 60 or 85 is energized and neither ribbon spool will be in a position for feeding, both detent pawls 99 and 77 will, through engagement with their ratchet shaped detent disks 98A and 75 hold both ribbon spools against a feeding movement. If it were not for the provision of this detent mechanism for both spools it is obvious that the rotation of both vertical drive shafts 16 and 83 would, through the frictional drive between the sleeve 25 and spool 38 for example, cause feeding of the ribbon from one spool to the other if the frictional driving forces were unequal for both spools. As a practical matter it is not possible to get the same frictional driving force for both spools and as a result there would be a tendency to feed the ribbon from one spool to the other during idle machine operations when the main shaft 10 is being rotated. This is an undesirable condition and the detent mechanism effectively prevents it from occurring.

Referring now to Fig. 1 it will be seen that the ribbon per se 100 extends from one spool to the other between a conventional platen 101 and a set of printing bars 102. The ink ribbon mechanism is preferably designed for use with the printing mechanism of the printing wheel type shown in the patent to R. E. Page and H. S. Beatie, No. 2,438,071, issued March 19, 1948. Such printing members 102 may also be reciprocable type bars or typewriter bars carrying type elements which are impressed in a percussive manner against the ribbon 100 and against a paper strip surrounding the platen 101. It will be recalled that while the ink ribbon is fed during the entire rotation of shaft 10, the ribbon is fed only a negligible amount during the time that the printing wheels of the aforesaid patent are

impressed against the platen 101. This is due to the decreased speed of shaft 10 at this time.

The normal diagonal position of the ribbon 100 was previously referred to and is shown in the diagrammatic view of Fig. 9, which diagonal position facilitates, with the machine at rest, the positioning of paper strips between the platen 101 and the printing mechanism. This position is attained because if neither solenoid 60 nor 85 is energized the left-hand ribbon spool 38 will be in its extreme upward position, due to the upward force of the spring 30 and the printing type will be aligned with the D area of the ribbon 100 at this end. Since the solenoid 85 is also deenergized the downward force of the spring 95 will force the ribbon spool 90 downwardly and, assuming that the high and low portions of cams 61 and 94 are effective, spool 90 will be down in such a position that inking will be derived at the right end from the B area. Therefore, the next position (Fig. 10) that the ribbon assumes and its direction of feeding is due to the fact that it is assumed that in the last operation of the machine the ribbon was previously feeding from the left to the right and the solenoid 85 will again be energized by electrical circuits to be subsequently described. However, if solenoid 60 was energized in the last operation it will again be energized to position ribbon 100 so that inking can be effected through the A area. Energization of solenoid 85 will then cause the ribbon spool 90 to be elevated as in Fig. 10 and the ribbon is now extended in a straight line so that inking can be obtained from the D area of the inking ribbon. When printing is effected through this area it is unwound from the spool 38 and wound onto the spool 90 and during the same operation cams 61 and 94 are rotated $\frac{1}{6}$ of a revolution to present high and low portions respectively in effective position. This will cause the ribbon spools to take a position shown in Fig. 11 so that the inking can now be derived from the C area.

Assuming now that the ribbon has been completely unwound from the spool 38 and that the electrical ribbon reversing mechanism to be subsequently described in detail has been rendered effective, the solenoid 85 will be deenergized, allowing the ribbon spool 90 to drop to provide inking from the uppermost or A area of the ribbon. The solenoid 60 now being energized will cause the left-hand spool 38 to be moved to the lowermost position to effect inking from the A area. After inking from this area the ribbon is now unwound from the right-hand spool 90 and wound around the left-hand spool 38 because the solenoid 60 places the left-hand spool 38 in position for being rotated. Printing is now effected through the A area of the ribbon 100 and the ribbon is fed an extent off the right spool onto the left spool 38 and cams 61 and 94 now rotate $\frac{1}{6}$ of a revolution, causing the low and high points of the respective cams to be simultaneously effective which thus elevates the ribbon spools at both ends so as to present the B inking area to the printing line. Thus, for successive printings there will be alternate inking from the A and B printing areas in succession until the ribbon 100 is fed completely unwound from the spool 90 and onto the spool 38 and after which time the direction of ribbon feed is automatically reversed and the C and D areas of the inking ribbon are used for inking the type of the printing mechanism.

The electrically controlled ribbon reversing mechanism includes electrical contacts which

are closed upon the complete unwinding of the inking ribbon from the associated inking spool; that is, when the last of the convolutions of the inking ribbon are being unwound from a spool these contacts may close by their inherent resiliency which initiates the reversal of the direction of the feeding of the inking ribbon.

Fig. 2 shows the contact operating mechanism associated with the right-hand spool. The spool carrier 105 of this spool is cut away to carry a bracket 106 (Figs. 2 and 7) upon which by a pivot pin 107 a contact operating arm 108 is mounted. A plate 109 of insulating material also carried by said spool carrier 105 carries a rigid contact carrying blade 110 and also a flexible contact blade 111, said blades carrying electrical contacts 112. The contact operating arm 108 has a button 113 of insulating material against which the resilient blade 111 presses so as to force the lower portion of said contact operating arm 108 through a slot in the right-hand ink supply spool 90. The innermost convolutions of the ink ribbon 100 are adapted to rock the arm 108 counterclockwise in Fig. 2 so that the button 113 bearing against the resilient blade 111 opens contacts 112. Obviously, when the last convolution of the inking ribbon is unwound from this spool there will be no restraint on the arm 108 and contacts 112 will close. This will cause the closure of circuits to be described later to initiate the reversal of the direction of the inking ribbon by deenergizing one solenoid and energizing the other.

Somewhat the same arrangement is provided for the left-hand ribbon spool wherein contacts 114 (Fig. 1) are similar to contacts 112. When the ink ribbon is fully unwound from the left-hand spool contacts 114 will close in the same manner.

A convenient means of securing electrical connections to the contacts 113 and 114 is provided consisting, as will be described, for only the left-hand ribbon spool, of diametrically different collector rings 116 (Fig. 5) which are insulatably carried by the ink ribbon spool carrier 32. Spring pressed contact plungers 117 and 118 continuously bear against the associated collector rings 116 and from said plungers electrical connections are made to the associated circuits. By suitable wires electrical connections are made between the collector rings 116 and the associated contacts 114 for the left-hand spool. A similar arrangement is also provided for the right-hand spool 90 as shown in Fig. 6. Also associated with each of the solenoids 60 and 85 are interlock contacts which are adapted to be normally closed when each solenoid is deenergized. The purpose of such contacts will be explained in connection with the wiring diagram. Associated with the solenoid 60 are contacts 120 (Fig. 5). When the solenoid 60 is deenergized the pin 70 abuts against an insulating block carried by the intermediate contact blade to close contacts 120. When solenoid 60 is energized contacts 120 open in an obvious manner. For the right-hand ink ribbon spool there are similar contacts 121 shown in Fig. 7 and controlled in the same way by its bell crank 93 and opened when solenoid 85 is energized.

Referring to the wiring diagram of Fig. 15 numerals 125 and 126 designate the supply lines for the electrical circuits. It will be assumed that sufficient ribbon is wound upon the right-hand and left-hand ribbon spools to have their respective contacts 112 and 114 open. Assuming

that in the previous operation of the machine the circuits were conditioned for feeding the ink ribbon from the left-hand spool to the right-hand spool, R3B contacts will be in their normal closed position. In the rest position of the machine the ribbon 100 is in the diagonal position of Fig. 9 and both solenoids 60 and 85 are deenergized. Upon starting up the machine, drive shaft 10 commences to rotate and such shaft rotates cams which close contacts CR145 and CR146. The times such contacts close and open are shown in Fig. 15 aside of each of these contacts and in degrees of rotation of shaft 10. At the end of the first machine cycle at 340° 15 cam contacts CR145 close to complete a circuit from the line side 125, cam contacts CR145, R3B relay contacts, pickup coil P of a duo wound relay R1, to line side 126. The latter closes its hold contacts R1A, and a hold circuit for R1 20 hold coil H is maintained through R1A contacts and CR146 cam contacts to 342° of the next cycle, it being obvious that CR146 cam contacts close at 357° of the last part of the first cycle before CR145 opens its contacts, and that CR145 25 closes its contacts at 340° before CR146 opens its contacts at 342°. This overlap in timing keeps the R1 relay energized in successive cycles, as long as R3B contacts are closed. R1 relay now having been energized at the end of the first 30 machine cycle it will transfer its R1B contacts completing a circuit from the line side 125 through R1B transferred contacts, interlocks contacts 120 now closed, solenoid 85 to line side 126. The parts are now in the position shown in Fig. 10; 35 the D area will be used for inking; and the ribbon will be fed in the arrow direction of Fig. 10. The Fig. 11 position has previously been explained in detail, solenoid 85 being maintained energized because R1 relay is kept energized by 40 the circuits just described.

When solenoid 85 is energized it opens the interlock contacts 121 to prevent any possibility of energizing the solenoid 60 in the event that some mechanical condition prevented the normal release of the core 91 of solenoid 85, thus preventing the possibility of both feeding mechanisms from being effective simultaneously, thereby destroying the ribbon. Contacts 121 are in the energizing circuit of solenoid 60 and now being open there is no possibility of improperly energizing solenoid 60.

The ribbon will keep on being wound on the right-hand ribbon spool, and being shifted up and down until the ribbon is completely unwound 55 from the left-hand spool, thus causing the closure of contacts 114 in the manner previously explained. By an obvious circuit R3 relay magnet is energized when contacts 114 close to open contacts R3B to deenergize the R1 relay and close contacts R3A. The center blade of such contacts latches below a spring-pressed latch arm 127 to hold R3B contacts latched closed. Thereafter when cam contacts CR145 close the pickup coil of the R2 duo-wound relay is energized, and held energized through the R2A relay contacts and cam contacts CR146 back to line side 125. R2 relay closes its R2B contacts, and while R1B contacts previously transferred back to normal position to deenergize the solenoid 85 a circuit to energize the solenoid 60 cannot be completed until the interlock contacts 121 are back to closed position, effected only when solenoid 85 is completely deenergized and its core 91 is at normal position. The energizing circuit for solenoid 60 is from line side 125,

11

R1B contacts now normal, R2B contacts now closed, contacts 121, solenoid 68, to line side 126. The parts are now in the position shown in Fig. 12 and the ribbon will be unwound from the right-hand spool and wound on the left-hand spool. When the right-hand spool is empty contacts 112 will close to energize by an obvious circuit the unlatch magnet 128 which rocks latch arm 127 to allow contacts R3A to open and contacts R3B to close. Solenoid 85 will now be energized and the ribbon will be wound back again on the right-hand spool.

While there have been shown and described and pointed out the fundamental novel features of the invention, it will be understood that various omissions and substitutions and changes in the form and details of the device illustrated and in their operation may be made by those skilled in the art without departing from the spirit of the invention. It is the intention, therefore, to be limited only as indicated by the scope of the following claims:

What is claimed is:

1. In an ink ribbon feed mechanism, two ink ribbon spools, driving means, a pawl and ratchet drive for each ribbon spool, cam means driven by the driving means and rotatable with the ribbon spools irrespective of their position for simultaneously positioning said ribbon spools to alternately shift said ink ribbon widthwise, separate solenoids for connecting, when energized, a related pawl and ratchet drive with said driving means when the ink ribbon is fed from the associated spool to the other, means controlled by both of said solenoids when one is energized and the other is deenergized for positioning, in accordance with the pawl and ratchet drive connected by the energized solenoid, both of said ink ribbon spools to render two lengthwise fields of said ink ribbon effective in one direction of ribbon feed, and two other lengthwise fields effective in the other direction of ribbon feed, and means controlled by said ribbon for energizing said solenoids in succession and deenergizing the previously energized solenoid.

2. In an ink ribbon feeding mechanism, the combination of two ink ribbon spools disposed at the ends of a printing device between which is an ink ribbon having four lengthwise inking fields, a pair of cam means for positioning and shifting both of said spools for shifting said ink ribbon for utilization of two of said four inking fields in succession as said ink ribbon is fed in one direction and for alternatively positioning and shifting both of said spools for shifting said ink ribbon for utilization of two other inking fields in succession as said ink ribbon is fed in another direction, means for rotating one of said spools for feeding said ribbon in said one direction thereon, other means for rotating the other spool for feeding said ink ribbon thereon in said other direction, a plurality of control means each for rendering the associated spool rotating means operative, and automatic means for causing either of said control means to render the associated spool rotating means operative for rotating one spool or the other for effecting the feeding of the ink ribbon in one direction or the other and correspondingly for causing said ribbon spool positioning and shifting cam means to position and shift said spools for utilization of either two lengthwise fields in succession in accordance with the direction of ink ribbon feed.

3. In an ink ribbon feed mechanism, two ink

12

ribbon spools, two drive shafts, two pawl and ratchet drives, each when rendered operable for causing a drive shaft to rotate the related ribbon spool, a pair of cam means each driven by the associated drive shaft and having one position for simultaneously shifting both of said ribbon spools to alternately shift said ink ribbon widthwise to ink from two lengthwise fields of the ink ribbon in one direction of ink ribbon feed, and having other positions for shifting both of said ribbon spools to alternately shift said ink ribbon lengthwise to ink from two other lengthwise fields of the ink ribbon in another direction of ink ribbon feed, and separate control means each operable in accordance with the direction of ink ribbon feed for rendering one or the other pawl and ratchet drives operable and for causing in accordance with the pawl and ratchet drive rendered operable the position of said cam means which effects the positioning of said ink ribbon spools to render two lengthwise fields of said ink ribbon effective in one direction of ink ribbon feed and the two other lengthwise fields of the ink ribbon effective in the other direction of ink ribbon feed.

4. In an ink ribbon feed mechanism, two ink ribbon spools, two drive shafts, a pawl and ratchet drives for each of said ribbon spools, each when rendered operable for causing a related drive shaft to rotate the related ribbon spool, a pair of cam means each driven by the associated drive shaft which have one position for simultaneously shifting both of said ribbon spools to alternately shift said ink ribbon widthwise to ink from two lengthwise fields of the ink ribbon in one direction of ink ribbon feed, and which have other positions for simultaneously shifting both of said ribbon spools to alternately shift said ink ribbon lengthwise to ink from two other lengthwise fields of the ink ribbon in another direction of ink ribbon feed, and automatic means operable in accordance with the desired direction of ink ribbon feed for causing a related pawl and ratchet drive to be rendered operable to rotate an associated ink ribbon spool by the related drive shaft and for positioning in accordance with the pawl and ratchet drive rendered operable both of said cam means to effect the positioning of said ink ribbon spools to render two lengthwise fields of said ink ribbon effective in one direction of ink ribbon feed and the two other lengthwise fields of the ink ribbon effective in the other direction of ink ribbon feed.

5. In an ink ribbon mechanism, the combination of ink ribbon spools carrying a reversible ink ribbon for printing elements which spools are normally positioned to position said ink ribbon diagonally with respect to said printing elements, separate control means each when operable for positioning the associated ink ribbon spool, ink ribbon reversing mechanism, and means controlled by said ink ribbon reversing mechanism for causing in accordance with the desired direction of ink ribbon feed one or the other of said control means to be rendered operable for positioning the related spool to shift one end of the ink ribbon to align said ink ribbon with said printing elements.

6. In an ink ribbon mechanism, the combination of ink ribbon spools carrying an ink ribbon for printing elements normally positioned for positioning said ribbon diagonally with respect to said printing elements, a plurality of drive means each when rendered operable for rotating the associated ribbon spool, separate control

13

means for positioning the related spool and rendering the associated drive means operable, ink ribbon reversing mechanism, and means controlled by said ink ribbon reversing mechanism for causing in accordance with the desired direction of ink ribbon feed one or the other of said drive means to be operable and for positioning the related spool to shift one end of the ink ribbon to align said ink ribbon with said printing elements.

7. In an ink ribbon mechanism, the combination of an ink ribbon having a plurality of longitudinal inking areas A, B, C and D, automatic ink ribbon reversing means to feed the ribbon in one direction and then the other, a pair of ink ribbon carrying spools for holding said ribbon in either of two different positions to select two different areas to be utilized for inking in each direction of ink ribbon feed, means controlled by said ink ribbon reversing means for shifting the pair of ink ribbon spools in one position to utilize two longitudinal areas A and B for inking in repeated alternation when said ink ribbon is fed in said one direction, and for shifting said pair of ink ribbon spools in another position to utilize two other longitudinal areas C and D for inking in repeated alternation when said ink ribbon is fed in said other direction, and cam means for reciprocating said pair of ink ribbon spools in either of their two positions to reciprocate the ink ribbon widthwise to utilize in accordance with the direction of ink feed selected two areas for inking therefrom in repeated alternation.

8. In an ink ribbon mechanism, the combination of an ink ribbon having a plurality of longitudinal inking areas A, B, C and D, means for feeding the ink ribbon in one direction, other means for feeding the ink ribbon in another direction, automatic ribbon reversing mechanism, means controlled by the ribbon reversing mechanism to cause said feeding means to feed the ribbon in one direction and then the other direction as the end of the ribbon is reached, means for holding said ribbon adapted to have either of two positions to provide a length of ribbon from which two different selected areas are utilized for inking in repeated alternation in each direction of ink ribbon feed, means for reciprocating said ribbon widthwise to utilize two longitudinal areas A and B for inking in repeated alternation when said holding means is in one position, and for reciprocating said ribbon widthwise to utilize two other longitudinal areas C and D for inking in repeated alternation when said holding means is in the other position, and means controlled by said ribbon reversing mechanism for shifting the holding means to one position when the ink ribbon is fed in said one direction to position the ribbon to enable said reciprocating means to shift the ribbon to utilize the A and B areas for inking in repeated alternation, and for shifting the holding means to another position when the ink ribbon is fed in the other direction to position the ribbon to enable the reciprocating means to shift the ribbon to utilize the C and D areas for inking in repeated alternation.

9. In an ink ribbon mechanism, the combination of an ink ribbon having a plurality of longitudinal inking areas A, B, C and D, means comprising ink ribbon carrying spools for holding said ribbon and adapted to have either of two positions to provide a length of ribbon from which two different selected areas are utilized for

14

inking in each direction of ink ribbon feed, means for rotating one spool for feeding the ink ribbon in one direction, other means for rotating the other spool for feeding the ink ribbon in another direction, automatic ribbon reversing mechanism, means controlled by the ribbon reversing mechanism to cause the rotation of said ink ribbon spools to feed the ribbon in one direction and then the other, rotatable cam means for reciprocating said ribbon spools widthwise to utilize two longitudinal areas A and B for inking in repeated alternation when said ink ribbon spools are in one position, and for reciprocating said ribbon spools widthwise to utilize two other longitudinal areas C and D for inking in repeated alternation when said ink ribbon spools are in the other position, means controlled by said ribbon reversing mechanism for positioning the ink ribbon spools in one position when the ink ribbon is fed in said one direction to enable said cam reciprocating means to shift the ribbon to utilize the A and B areas for inking in repeated alternation, and for positioning the ink ribbon spools in another position when the ink ribbon is fed in the other direction to enable the reciprocating means to shift the ribbon to utilize the C and D areas for inking in repeated alternation, and means for rotating said cam reciprocating means.

10. In an ink ribbon mechanism, the combination of an ink ribbon having a plurality of longitudinal inking areas A, B, C and D, a pair of ribbon carrying spools adapted to have either of two positions to provide a length of ribbon from which two different selected areas are utilized for inking in each direction of ink ribbon feed, means for rotating one ink ribbon spool for feeding the ink ribbon in one direction, other means for rotating the other ink ribbon spool for feeding the ink ribbon in another direction, automatic ribbon reversing mechanism, means controlled by the ribbon reversing mechanism to cause the rotation of one spool or the other to feed the ribbon in one direction and then the other, means for reciprocating both of said ribbon spools widthwise to utilize two longitudinal areas A and B for inking in repeated alternation when said ink ribbon spools are in one position, and for reciprocating both of said ribbon spools widthwise to utilize two other longitudinal areas C and D for inking in repeated alternation when said ink ribbon spools are in the other position, and means controlled by said ribbon reversing mechanism for positioning the ink ribbon spools in one position when the ink ribbon is fed in said one direction for reciprocation of the ribbon to utilize the A and B areas for inking in repeated alternation, and for positioning the ink ribbon spools in another position when the ink ribbon is fed in the other direction for reciprocation of the ribbon to utilize the C and D areas for inking in repeated alternation.
